UNITED STATES PATENT OFFICE

2,435,468

LUBRICATING PUMP

Fredrich J. Rode and Meredith R. Hatch, Toledo,
Ohio, assignors to E. W. Bliss Company, Brooklyn, N. Y., a corporation of Delaware

Application September 21, 1943, Serial No. 503,226

6 Claims. (Cl. 184—28)

1

This invention relates, as indicated, to lubricating pumps, but has reference more particularly to a manually-operated pump which has been designed primarily to be used in a system in which there is located a plurality of feeders which operate to charge and discharge measured quantities of a lubricant in response to flow and counterflow of the lubricant through the system.

A primary object of the invention is to provide a pump of the character described in which certain of the elements comprising the pump are designed to perform a plurality of functions. Among these elements are a cylinder which serves not only as a distributing valve which may be rotated to effect optional distribution in either of two directions, but also as a cylinder for the lubricant feeding piston or plunger, an element which serves not only as a return valve for excess lubricant but as an indicator to denote the return of such excess lubricant to the pump, and a handle which serves not only to feed the lubricant but to rotate the aforesaid cylinder to its optional positions as well as a means of returning the aforesaid indicator to its initial position.

Another object of the invention is to provide a pump of the character described which is of sturdy and compact construction, and well adapted for use in a lubricating system such as referred to above.

Other objects and advantages of the invention will be apparent during the course of the following description.

In the accompanying drawings, forming a part of this specification, and in which like numerals are employed to designate like parts throughout the same.

Fig. 1 is a side elevational view of a lubricating pump embodying the invention;

Fig. 2 is a top plan view of the pump, with the cover removed;

Fig. 3 is a front elevational view of the pump;

Fig. 4 is a fragmentary cross-sectional view, taken on the line 4—4 of Fig. 3, and

Fig. 5 is a fragmentary cross-sectional view, taken on the line 5—5 of Fig. 4.

Referring more particularly to the drawings, the pump will be seen to comprise a pump body 1, having a bracket portion 2 and laterally extending lugs or ears 3 whereby the pump may be secured to a suitable support or supporting structure (not shown).

Mounted on the pump body 1 is a cylindrical chamber or reservoir 4 which is adapted to contain a supply of grease or other lubricating medium,

access to this reservoir for the purpose of filling the same being had through the top thereof, which is normally closed by means of a closure or cap 5, which is pivotally secured to the reservoir 4, as at 6.

The pump body 1 has a cylindrical opening 7 therein, in which is mounted a valve 8, preferably formed of hard brass, and having a plurality of radial passageways 9, 10, 11, 12 and 13 therein. The passageways 9, 10, 11 and 12 extend from the periphery of the valve 8 to an axially extending passageway or chamber 14, and the passageway 13 extends inwardly from the periphery of the valve to a point short of the passageway 14, communicating with a chamber or recess 15 in a reduced rear portion 16 of the valve through an angularly extending passageway 17.

The chamber 15 has an opening 18 in the wall 20 thereof which extends through an angle of approximately 60 degrees, and this opening is at all times in communication with a radial passageway 19 in the pump body 1, which passageway is closed at its outer end by means of a plug 20. The passageway 19 is in communication with one end of a longitudinally extending passageway 21 in the pump body, the passageway 21 intersecting a vertically extending passageway 22 in the pump body which interconnects the interior of the reservoir 4 with certain of the radial passageways in the valve 8.

The valve 8 is maintained against axial displacement from the pump body by means of a front cover and a rear cover. The front cover 35 consists of an upper portion 23 and a lower portion 23a, the latter provided with forwardly extending projections 24 which serve as stops, as will be presently explained. The cover parts 23 and 23a are secured to the pump body, as by means of screws 25, and the rear cover 26 is secured to the pump body as by means of screws 27. A packing leather 28 is interposed between the front cover and the pump body, and a packing leather 29 is interposed between the valve 8 and the pump body.

The radial passageways 9, 10, 11 and 12 are provided with ball checks 30.

Mounted for reciprocal movement in the axially extending chamber 14 of the valve 8 is a plunger 31, the intermediate portion of which extends through a gland nut 32, which through pressure on packing 33, serves to prevent leakage of the lubricating medium through the front of the valve 8.

The valve 8 is further provided with a pair of

spaced downwardly extending ears 34, to which a link 35 is pivotally connected, the other end of this link being pivotally connected to the lower end of a handle 36, which is pivoted, as at 37, to the forward end of the plunger 31. The handle 36, it may be noted, is provided at its lower end with inturned portions 38, which serve a purpose to be presently described.

The pump further includes a valve 39, which is mounted for reciprocal movement in the passageway 21 in the pump body, this valve having a piston 40 at its rear end, which is connected to the valve by a portion 41 of reduced diameter. The valve 39 further includes an indicator head 42 of enlarged diameter. A set screw 43, bearing against a flattened area 44 of the valve 39 serves to maintain the valve within predetermined limits of axial movement.

The pump body 1 is provided in the lower portion thereof with passageways or ports 45 and 46, to which conduits 47 and 48 are respectively connected. The conduits 47 and 48 are connected to a lubricating system diagrammatically indicated by the line 49, and in which may be located a plurality of lubricating outlets or feeders 50. These feeders may be similar to the feeders in the lubricating system described in the U. S. patent to Hillis Re. 21,160.

With an understanding of the construction of the pump, as described, the operation thereof will now be briefly described.

Assume that the handle 36 is in the solid line position shown in Fig. 3, to which position it has been brought by rotation thereof in a counter-clockwise direction until one of the ears 34 comes into engagement with the right-hand stop 24. With the handle in this position, the passageway 22 in the pump body is in communication with the radial passageway 9 in the valve 8. The radial passageway 11 in the valve is in communication with the port 45, and the passageway 13 is in communication with the port 46. The valve 39 is in its innermost axial position, as shown in Fig. 4 so that lubricant may flow from the reservoir 4 around the reduced portion 41 of the valve and into the passageway 22 in the pump body.

The operator, if he wishes to supply the grease or other lubricant to the outlets 50, will pull the handle 36 away from the reservoir 4, causing the plunger 31 to move and create a suction or vacuum in the chamber 14, thereby drawing the grease from the reservoir 4 into this chamber. The extent of outward movement of the plunger 31 will be limited by virtue of the engagement of the inturned ends 38 of the handle with the lower surfaces of the ears 34, which thus serve as stops. Upon the return stroke of the handle 36, the grease in the chamber 14 will be forced by the plunger 31 out of this chamber into the radial passageway 11, thence through port 45, conduit 47, and line 49 to the outlets 50.

The aforesaid operation is continued until the line 49 has become completely filled with grease, and the excess grease is returned to the pump through line 49, conduit 48, port 46, passageways 13 and 17, chamber 15, opening 18 and passageways 19 and 21.

The return of the grease to the pump will be indicated by outward movement of the indicator head 42, which is brought about by the pressure of the returning grease in the passageway 21 upon the piston 40. The valve 39 will, in this way, be forced outwardly from the passageway 21 to such an extent that the grease will ultimately be forced

into the passageway 22 and thence back into the reservoir.

Under certain conditions, it becomes desirable to force the grease through the line 49 in a direction opposite to that which has been described. For this purpose, the handle 36 is moved to the dotted line position shown in Fig. 3, to which position it has been brought by rotation thereof approximately 60 degrees in a clockwise direction, 10 that is, until one of the ears 34 comes into engagement with the left hand stop 24.

This results in the radial passageway 12 being brought into registration with the passageway 22, the radial passageway 10 into registration with the port 46, and the passageway 13 into registration with the port 45. Upon operation of the handle 36 in the manner already described, the lubricating grease will be discharged from the chamber 14 through passageways 10, port 46, conduit 48, line 49, and to outlets 50, the lubricant returning through line 49, conduit 47, port 45, passageways 13 and 17, chamber 15, opening 18 and passageways 19 and 21, the indicator head 42 being moved in the manner already described to denote the return of the lubricant to the pump.

It will be noted that by moving the handle 36 to a substantially vertical position, the handle, upon movement thereof towards the reservoir 4, will serve to push the indicator head 42 inwardly, 30 thereby returning the valve 39 to its initial position.

It is thus seen that we have provided a lubricating pump having incorporated therein a number of highly advantageous features, among which 35 may be mentioned a cylinder which serves not only as a distributing valve which may be rotated to effect optional distribution in either of two directions, but also as the cylinder for the lubricant feeding piston or plunger, an easily visible and actuated indicator for signalling the return of the excess lubricant to the pump, and a handle which serves not only to feed the lubricant but to rotate the aforesaid cylinder to its optional 40 positions as well as a means of returning the aforesaid indicator to its initial position.

It is to be understood that the form of our invention, herewith shown and described, is to be taken as a preferred example of the same, and that various changes in the shape, size and arrangement of parts may be resorted to, without departing from the spirit of our invention, or the scope of the subjoined claims.

Having thus described our invention, we claim:

1. In a pump of the character described, a 55 pump body, a valve mounted in said body, a plunger mounted in said valve for reciprocal movement therein, and a handle pivotally secured to said valve and to said plunger, said handle operable upon movement in one plane to change the position of said valve with respect to said body, and operable upon movement in a plane normal to said first-named plane to reciprocate said plunger, and means on said handle and valve coactable to limit the movement of said plunger from said valve comprising a hook-shaped end on said handle which coacts with ears extending from said valve.

2. In a pump of the character described, a 70 pump body, a valve mounted in said body and rotatable to a plurality of selected positions, said valve having an axial chamber therein; a plunger in said chamber, said body having a passageway therein parallel with said chamber, a second valve mounted for reciprocal movement in said 75 passageway and being movable in one direction

by fluid pressure in one end of said passageway; means for connecting said chamber with the one end of a closed lubricating fluid system; and means for connecting said one end of said passage with the opposite end of said lubricating system, said last named valve having an indicator head extending exteriorly of the pump body whereby the position of said head indicates the entrance of fluid into said passageway.

3. In a pump of the character described, a pump body; a valve mounted in said body and movable about its axis to a plurality of selected positions, said body having a passageway therein parallel with the axis of said valve; a second valve mounted for reciprocal movement in said passageway and being movable from an initial position by fluid pressure in one end of said passageway; means for connecting said valve with one end of a closed lubricating fluid system; means for connecting said one end of said passageway with the opposite end of said closed lubricating system, said last named valve having an indicator head disposed exteriorly of the pump body whereby the position of said head indicates entrance of lubricant into said passageway; and manually operated means for returning said last named valve to its initial position.

4. In a pump of the character described, a pump body; a valve mounted in said body and movable to a plurality of selected positions to vary the distribution of a lubricant from said pump; a plunger mounted for reciprocal movement in said valve, said body having a passageway therein; and indicator element in said passageway movable from an initial position by fluid pressure entering said passageway; means for connecting said valve body with one end of a closed lubricating fluid system; means for connecting said passageway with the opposite end of said lubricating system; and a handle for reciprocating said plunger, said handle being engageable with said indicator element for moving said element to its initial position.

5. In a pump of the character described, a pump body; a valve mounted in said body and movable to a plurality of selected positions to vary the distribution of a lubricant from said pump; a plunger mounted for reciprocal movement in said valve, said body having a passageway therein; an indicator element in said passageway movable from an initial position by fluid pressure in said passageway; means for connecting said valve with one end of a closed lubricat-

ing fluid system; means for connecting said passageway with the opposite end of said lubricating system; and a handle for reciprocating said plunger and for rotating said valve to said selected positions, said handle being operable, when the valve is in a position intermediate said selected positions to return said indicator element to its initial position.

6. In a pump of the character described, the pump body; a lubricant reservoir mounted thereon; a valve mounted in said body and rotatable to a plurality of selected positions, said valve having an axial chamber therein and a passage leading from said chamber radially to the periphery of the valve, said body having a passageway leading from said reservoir to the periphery of said valve and being alignable with said radially extending passage, said body having a second passageway therein extending parallel with said chamber and intersecting the first mentioned passageway in said body; a second valve mounted for reciprocal movement in said second passageway and movable by fluid pressure in one end of said passageway; means for connecting the first mentioned valve with one end of a closed lubricating system and means for connecting said one end of said second passageway with the opposite end of said lubricating system, said last named valve having an indicator head disposed exteriorly of the pump body whereby the position of said head indicates the entrance of lubricant into said passageway.
